UNITED STATES PATENT OFFICE.

ERNEST E. YAXLEY, OF CHICAGO, ILLINOIS.

MAGNETO-BELL RINGER.

SPECIFICATION forming part of Letters Patent No. 697,698, dated April 15, 1902.

Application filed December 6, 1901. Serial No. 84,931. (No model.)

To all whom it may concern:

Be it known that I, ERNEST E. YAXLEY, a citizen of the United States, residing at Chicago, in the county of Cook and State of Illinois, have invented a new and useful Improvement in Magneto-Bell Ringers, of which the following is a specification.

My invention relates to improvements in magneto-bell ringers of the type commonly employed upon electric telephones.

My object is to provide certain improvements, particularly in the construction of the armature-support, whereby it may be readily moved to adjust the armature with relation to the magnet-cores and operates to hold the parts in adjusted position with great security.

In the drawings, Figure 1 is a view in elevation of a magneto-bell ringer constructed with my improvements; Fig. 2, a section taken on line 2 in Fig. 1 and viewed in the direction of the arrow, and Fig. 3 a section on line 3 in Fig. 2.

A B are electromagnets having cores A' B' secured at their ends at one end of the magnets by means of screws a to the attaching bar or yoke C. The permanent magnet D is secured to the yoke C by the screw b. On the ends of the electromagnet-spools adjacent to the yoke C are disks c, of insulating material, which fit around the cores. The conducting-wires X where they leave the magnets are looped around the spool-flanges through perforations therein and pass out beneath the disks c, which clamp the wires and prevent them from contacting with the yoke C. At the opposite ends of the magnets the cores project a distance beyond the ends of the spools sufficient to present threaded end portions d, as shown in Fig. 3.

E is a yoke of brass or other suitable non-magnetic material provided between its ends on opposite sides with parallel projecting flanges or ears e e' and having openings e² toward opposite ends to fit loosely over the threaded core ends d.

The armature F consists of a plate of suitable metal provided near opposite ends with hard-metal contacts f and midway between

its ends in opposite sides with shallow bearing-sockets f' f''. The socket f'' receives the 50 pointed end of a bearing-pin g on the ear e, and extending through a threaded opening in the ear e' is an adjustable bearing-screw g', pointed at its inner end to engage the socket f' of the armature. Thus the armature is 55 pivotally held by the pin g and screw g', the latter being adjustable and carrying a locking-nut g², whereby it may be securely fastened in adjusted position. The yoke E is secured to the cores A' B' between clamping-nuts h h', adjustable on the threaded ends d. The contacts f register with the centers of the ends of the cores, and the armature is positioned with relation to the cores by adjusting the yoke E on the threaded ends d. This adjustment is effected by loosening and turning the clamping-nuts h h', and they are caused to press firmly against opposite sides of the yoke when the proper adjustment of the armature is effected. The armature carries midway between its ends the bell-striker F'.

The principal feature of novelty lies in the construction of the means described for positioning and holding the armature. The elongated cores presenting the threaded end portions d with the clamping-nuts h h' form a very desirable means for regulating the adjustment of the armature-carrying yoke. The construction is particularly strong and durable, and the yoke is held firmly against loosening when once adjusted.

What I claim as new, and desire to secure by Letters Patent, is—

In a magneto-bell ringer, the combination of electromagnets having cores presenting 85 projecting, threaded end portions, an armature-support comprising a yoke having openings to receive said cores, and adjustable nuts on each of the threaded end portions of the cores clamping the yoke between them, 90 substantially as and for the purpose set forth.

ERNEST E. YAXLEY.

In presence of—

ALBERT D. BACCI,
WM. B. DAVIES.
